UNITED STATES PATENT OFFICE.

EMIL DEISTER, OF FORT WAYNE, INDIANA.

PROCESS OF AND APPARATUS FOR CONCENTRATING OR CLEANING COAL.

Application filed May 3, 1922. Serial No. 558,220.

To all whom it may concern:

Be it known that I, EMIL DEISTER, a citizen of the United States, residing at Fort Wayne, in the county of Allen and State of Indiana, have invented new and useful Improvements in Processes of and Apparatus for Concentrating or Cleaning Coal, of which the following is a specification, reference being had to the accompanying drawings.

The present invention relates to certain improvements in the process of and apparatus for concentrating and separating the waste material or refuse from coal, and particularly to that class thereof commonly known as dry concentration and dry concentrators, wherein a differentially reciprocated table is used upon which the stratification of the materials according to their specific gravity is accomplished by an air cushion.

Heretofore, dry concentration has been practiced on a table having its concentrating surface formed of pervious material, such as silk, through which air under pressure is forced in an upward direction. This current of air floats the particles of the material fed to the table, the heavier particles tend to settle to the previous surface under the influence of the reciprocating motion of the table. To aid in the retention of the stratification of the materials thus obtained riffle cleats have been applied on the pervious surface which extend from the head or motion end of the table toward the opposite end. The particles caught by the riffle cleats under the influence of the reciprocating movement of the table are advanced forwardly, and since the cleats are tapered longitudinally the lighter particles caught by the cleats are gradually eliminated from the channels formed by the cleats. Such a process for its successful operation requires that the material shall be very closely sized previous to concentration which is objectionable because it is very expensive and requires much power and floor space.

In an attempt to obviate the close sizing of the material referred to longitudinal impervious channels have been formed on the pervious surface of the table so that a pervious section lies between each two impervious channels. The air is blown upwardly through the pervious sections as before and the heavier particles of material closest to the pervious sections drop into the

impervious channels in which they advance forwardly under the influence of the reciprocating movement of the table. The channels decrease in depth gradually from the head end of the table toward the opposite end so that as the caught materials advance forwardly therein the finer particles settle to the bottom of the channels and crowd the coarser and lighter particles out over the top of the same. Furthermore, the tiny air passages in the pervious surface readily become choked or clogged with dirt and the rubbing or sliding action of the material on the fabric soon wears out the latter. Also the directly vertical or straight upward air currents lift the finer particles constantly and thereby prevent perfect stratification of the materials. Hence this process is not entirely practicable, especially in the cleaning of coal for the production of metallurgical coke.

It is well known that coking coal that does not require cleaning is rapidly being exhausted; but there are large supplies of low grade coking coal which require cleaning of its refuse before it can be converted into coke. This cleaning of the low grade coal should be accomplished, preferably, by the dry concentration method in order that the coal may be placed in a dry state into the coking ovens and thereby avoid drying of the same by costly natural or artificial means, it being essential where the wet method is used for the cleaning of coal to dry the cleaned coal before placing it in the coking ovens. In cleaning this low grade coal by the dry method it is essential that the machine shall be efficient and shall have large capacity and shall require in its operation a minimum of air under pressure and a minimum of floor space, and since close sizing of the coal is costly it is also desirable that such sizing shall be eliminated as much as possible.

The object of my invention is to provide a method of dry concentration and apparatus embodying the same by which comminuted materials, especially coal for use in the production of metallurgical coke, may be efficiently, cheaply and thoroughly cleaned of refuse and also obviate the necessity of previous close sizing of the material, and eliminating the disadvantages of previous processes and apparatus above referred to.

In the following description of the invention I shall refer to it as applied to the

cleaning of coal, it being understood that by such reference I do not intend to limit the invention to the cleaning of coal but to include herein the concentration of all materials for which the invention may be adapted.

I have found that by providing a differentially reciprocating table having the form of a trough or channel, the concentrating 10 surface of which is preferably V-shaped transversely or sloped upwardly laterally in opposite directions, the channel extending substantially the length of the table, with an impervious covering and introducing air under pressure into the bed of material fed onto the table in a direction substantially parallel to and along the concentrating surface of the channel, the air being introduced along the said concentrating 20 surface and directed toward the middle of the channel, the draft of air not only floats the lighter material or coal but also tends to assist the heavier material toward the said portion of the channel, along which 25 channel the latter material is advanced toward the refuse discharge end of the table under the influence of the reciprocating motion of the table. The waste matter or refuse in coal generally has a greater specific 30 gravity than the coal hence the waste settles to the bottom of the channel and the coal stratifies above it since the draft of air as introduced first meets the heavier particles adjacent to the sloping concentrating 35 surface of the channel without lifting them into the upper strata, and then curves and filters up through the bed of material causing the lighter particles to float and at the same time it drives and assists the 40 heavier particles toward the middle portion of the channel.

By constricting the channel laterally toward the upper discharge end of the table and also gradually decreasing it in depth 45 toward said end the heavier particles, or waste, are required to climb the slope of the channel longitudinally toward the discharge end of the table and to crowd the coal or lighter particles toward the sides of 50 the channel over which they pass, the heavier particles or waste passing off at the upper end of the channel.

The introduction of the air under pressure to the concentrating surface of the 55 channel in the manner described above is most important to the process and causes a complete separation of the waste material from the lighter material or coal in strata. There is, therefore, no pervious covering on the table yet air under pressure is introduced effectively and distributed all over its concentrating surface and the stratification of the material in the channel is maintained throughout its length.

60 In the drawings, Figure 1 is a plan view

of my preferred form of apparatus for carrying out the invention; Fig. 2 a side elevational view of the same; Fig. 3 an end view of the table; Fig. 4 a cross-sectional view on line 4-4 of Fig. 1; Fig. 5 a cross-sectional view on line 5-5 of Fig. 1; Fig. 6 an enlarged fractional view of the deck illustrating the air discharging means; Fig. 7 a plan view of the forward or discharge end of the table; Fig. 8 an end view of the latter; Fig. 9 a plan view of the covering and Fig. 10 an elevational view of the same.

In the drawings 10 indicate suitable foundations or pedestals upon which the driving mechanism 11 and the table are supported. The driving mechanism is suitably connected to the table 12 and a coiled spring 13 connected to the table and adjustably mounted in a bracket 14 opposes the reciprocation of the table in one direction and also places the proper tension thereon. The table is suitably mounted for reciprocation by the sliding supports 15, as shown in Fig. 3. The supports form no part of my present invention. The driving mechanism 11 may be any suitable mechanism which will differentially reciprocate the table, that shown in the previous Patent No. 1,088,682, being well adapted for my present purpose.

The table comprises the bottom member 17, two side members 18, the central longitudinal stringer 19, the lateral upwardly inclined stringers 20 secured to the side members and to the stringer 19 and the bottom members 21 of the channel or trough 22 which are secured in suitable manner to the frame work thus formed, the said members 21 forming a substantially V-shaped bottom or floor. The side members 18 gradually approach each other toward the discharge end of the table as shown in Fig. 1 and in like manner the bottom of the channel or trough 22 gradually decreases in width toward the said end. The said bottom is also inclined upwardly at a suitable angle toward the discharge end of the table. Hence the channel or trough is constricted both laterally and vertically from the head or motion end of the table toward the opposite end thereof.

A guard 23 projects above the upper edge of the side members 18 and the end member at the head end of the table, the guard terminating at a suitable point forwardly of the said head end at about which the lighter particles of material will tend to roll over the upper edges of the side walls 18 or fall out of the channel, as hereafter described. A suitable feed mechanism (not shown) will be positioned at the head end of the table to feed the material to be concentrated into the channel.

The cavity 24 beneath the bottom of the channel or trough 22 forms an air tight box, the bottom member 17 being apertured at

suitable points into which apertures are suitably connected a suitable number of tubes 25. A flexible conduit 26 is connected to each tube 25 and to a branch pipe 27 5 connected to a main air supply pipe 28, each branch pipe having a controlling valve 29 therein. A suitable blower, not shown, is connected to one end of the air pipe 28. The partitions 30 and 31 extend across the 10 air box transversely and divide the same into three compartments 32, 33 and 34, the flexible conduits having communication with the compartments respectively. Hence, by means of the valves 29 the quantity of air 15 which shall enter the several compartments is controlled as conditions may require.

Preferably the bottom members 22 are formed of suitable strips of wood 35, preferably laid parallel to the side walls 18, 20 and they are spaced transversely to form the slots 36 extending longitudinally of the channel.

On top of the wooden strips 35 are placed a series of overlapping strips 37 of suitable 25 material, such as rubber, having its lower surface provided with fine transverse corrugations 38, the smooth side of the strips 37 being on top and forming the concentrating surface of the channel 22. The fine 30 corrugations 38 therefore form small channels or jets 39 between the overlapping strips 37 which communicate with the slots 36 and open at their outer ends into the channel 22, the jets being substantially parallel to the concentrating surface of the channel. Hence the air discharging from the jets is introduced into the channel in a 35 direction substantially parallel to the top surfaces of the corrugated strips which form the concentrating surface of the table, and also along the said surfaces, as shown in detail in Fig. 6. The several corrugated strips are secured in position in suitable manner, as by the suitable thin strips 40, 40 preferably of metal, through which and through the corrugated strips are passed suitable fastening means, such as nails, the latter being engaged in the wood strips 35.

Suitable aprons 41 are secured along the 50 upper edge of the sides of the table and a suitable apron 42 is provided at the discharge end of the table.

In order to control the pressure of the air in the forward compartment 34, I provide a valve 43 in the outer wall thereof, by opening which, more or less of the pressure may be released and thereby secure a very refined control of the materials in the channel 22 adjacent to the discharge end 55 of the table, it being apparent that by slightly releasing the pressure of the air on the materials the frictional contact of the materials on the bottom of the channel is increased and hence under the influence of the reciprocation movement of the table they

progress more rapidly toward the discharge end. This is desirable where there is a large percentage of refuse at said end of the table.

At the discharge end of the table I mount 70 a gate or bucking plate 44, (Figs. 7 and 8), having a V-shaped slot or cut-out portion 45 therein. The gate is mounted on the bolts 46 which project through the slots 47 formed in the opposite sides of the gate and is secured in adjusted vertical position by the wing nuts 48. By adjusting the vertical position of the gate the materials advancing toward the discharge end may be held back more or less in order to increase the 75 depth of the bed of material at said end and crowd the coal successfully over the sides of the table, as conditions may require.

At suitable points upon the upper edge of the opposite side boards of the channel 22, I pivot a number of gates 49 which when open as shown in the drawings cut out more or less of the clean coal as required and direct the same off the table, and if there is a large percentage of refuse at said end of the channel the gates will be closed in order that the refuse shall pass off the table at said end. In other words, the gates 49 will be adjusted in accordance with the 80 percentage of refuse contained in the coal. 90

At suitable points on the table I may mount the diverters 50, preferably stationary as shown, which may be raised or lowered as desired to divert the upper strata of clean coal in the middle portion of the 100 table toward the opposite sides thereof. The diverter comprises the blades 50' arranged at a suitable angle to the longitudinal axis of the table and secured to a bar 51 secured to a bolt 52 extending through a cross member 53 supported on the foundation 10, by the standards 54. By rotating the nuts 54' on the bolt in proper direction, the diverters may be raised or lowered as desired. Any 110 suitable means for adjustably supporting the diverters will suffice for my purpose.

Preferably, the concentrating surface of the channel adjacent to the feed end is level longitudinally in order to increase the capacity of the table and to advance the material rapidly to the point approximately where the coal begins to discharge over the sides of the channel from which point the said surface is inclined upwardly toward the discharge end B. 115

Any suitable gaseous medium for stratifying the materials will suffice.

In operation, the coal and refuse mixture in a crushed state is continuously fed into the deeper and wider end portion of the channel adjacent to the head or motion end A of the table. The table is differentially reciprocated by the driving mechanism and air or other gaseous medium is forced into the air box from which it is projected in the 120 125 130

form of lateral jets into the channel 22. The mixture drops by gravity toward the bottom of the channel and encounters the air currents, the heavier materials settling 5 to the said bottom and gradually building up in depth without being lifted by the air currents and the lighter materials being floated by the air currents and stratified. The motion of the table impels the materials up the channel toward the discharge end B thereof. Since the channel is restricted or tapered both transversely and longitudinally the clean coal being the upper strata of material passes over the upper 10 side edges of the channel as the bed of materials is crowded into the progressively restricted channel. The diverters direct all clean coal travelling forward in the middle of the channel toward the upper side edges 15 of the channel, the discharge of the refuse being controlled by the adjustable end gate and the pressure and quantity of the air being controlled by the several valves as 20 conditions may require.

25 5. What I claim is:

1. In a concentrating and separating table having its top surface inclined both longitudinally and transversely, means to reciprocate the table longitudinally, means under 30 the surface of the table to form a plurality of transverse fine air channels adapted to project jets of a gaseous medium substantially parallel to and across said surface and means to supply air under pressure to said 35 channels.

2. In a concentrating and separating table having its top surface inclined both longitudinally and transversely, means to reciprocate the table longitudinally, a plurality 40 of transversely corrugated strips extending from end to end of the table and forming transverse air channels on said surface and means to supply air under pressure to said 45 channels.

3. In a concentrating and separating table having its top surface inclined both longitudinally and transversely, means to reciprocate the table longitudinally, a plurality 50 of overlapped transversely corrugated strips extending from end to end of the table and covering said surface and adapted to form transverse air channels thereon, and means to supply air under pressure to said 55 channels.

4. A concentrating and separating table 60 having a longitudinally disposed channel tapering both transversely and longitudinally from the head end of the table toward the opposite end thereof, the bottom or concentrating surface of the channel being also transversely inclined in opposite directions, means to introduce a gaseous medium laterally into the channel and means to reciprocate the table.

5. A concentrating and separating table 65 having a longitudinally disposed channel adapted to retain material, a plurality of longitudinally disposed transversely corrugated strips of material on the bottom of the channel and forming the concentrating 70 surface thereof, the spaces between the corrugations forming a plurality of channels substantially parallel to said surface, means to supply a pressure of a gaseous medium to the latter channels and means to reciprocate 75 the table.

6. A concentrating and separating table 80 having a longitudinally disposed channel adapted to retain material, a plurality of overlapped longitudinally disposed transversely corrugated strips of material on the bottom of the channel and forming the concentrating surface thereof, the spaces between the corrugation forming a plurality 85 of channels substantially parallel to said surface, means to supply a pressure of gaseous medium to the latter channels.

7. In a concentrating and separating table 90 the combination of a trough-like structure having its bottom formed of oppositely inclined members relatively to the transverse axis of the table and also inclined upwardly from the head end of the table toward the opposite end thereof, the sides of the trough also inclining toward each other from the 95 said head end to the said opposite end of the table, a covering on the said bottom formed of a plurality of transversely corrugated strips of material longitudinally disposed on said bottom, the said strips being 100 overlapped to form between them a plurality of air channels, means to supply a pressure of air to said channels and means to reciprocate the table.

8. In a concentrating and separating table 105 the combination of a deck having a trough-like channel therein which tapers longitudinally and transversely from the head end of the table toward the opposite end thereof, the bottom of the channel being V-shaped 110 transversely, a concentrating surface on said bottom formed by a plurality of overlapped, transversely corrugated strips of material disposed on said bottom, the said strips forming between them a series of air channels, means to supply a pressure of air to the latter channels, means to selectively control the said supply of air, and means to reciprocate the table.

9. In a concentrating and separating table, the combination of a deck having a channel adapted to retain material, means to introduce a gaseous medium laterally into the material for stratifying the same, means to reciprocate the table, for advancing the material toward the discharge end of the table, means at the discharge end of the table for controlling the discharge of the 125

heavier materials and means to control the direction of movement of the upper strata of material.

10. In a concentrating and separating table, the combination of a deck having a longitudinally disposed channel adapted to retain material, the bottom of the channel having a concentrating surface formed of a series of overlapped, corrugated strips of material, the said strips forming between them a series of air channels having communication with the main channel, means having communication with the air channels for supplying thereto a pressure of air, means to selectively control the said supply, means at the discharge end of the channel for controlling the discharge of the heavier materials, means to control the direction of movement of the lighter material and means to reciprocate the table.

11. In a concentrating and separating

table, the combination of a deck having a longitudinally disposed channel adapted to retain material, and being tapered both longitudinally and laterally from the head end 25 of the table toward the discharge end of the same, a covering on the bottom of the said channel formed of a series of corrugated strips of material overlapped and forming between them a series of air channels having 30 communication with the main channel, means having connection with the air channels for supplying selectively a pressure of air for stratifying the materials in the main channel, means to reciprocate the table, 35 means to regulate the discharge of the heavier materials at the discharge end of the channel and means to control the discharge of the lighter materials.

In witness whereof I have hereunto subscribed my name this 1st day of May, 1922.

EMIL DEISTER.
